UNITED STATES PATENT OFFICE.

WILLIAM A. WEIL, OF GLENCOE, OHIO.

FORCE-FEED LUBRICATOR.

1,083,166.

Specification of Letters Patent.

Patented Dec. 30, 1913.

Application filed July 27, 1912. Serial No. 711,853.

To all whom it may concern:

Be it known that I, WILLIAM A. WEIL, citizen of the United States, residing at Glencoe, in the county of Belmont and State 5 of Ohio, have invented certain new and useful Improvements in Force-Feed Lubricators, of which the following is a specification.

My invention relates to lubricators, and 10 particularly to force feed lubricators designed to work against steam pressure.

The principal object of my invention is the provision of a very simple, compact and effective force feed lubricator, readily put 15 in place or removed, readily adjusted to suit various conditions of operation, and adapted to preserve a uniform pressure of the lubricant against the pressure of steam or like fluid.

20 A further object is to provide a force feed lubricator in which the pump therefor is so constructed as to be extremely compact and in which a direct engagement is secured between the driven shaft and the 25 piston without the necessity of mechanism interposed between the two or transmitting the movement of the driven shaft to the piston.

30 A further object is to provide in connection with a force feed lubricator, an actuating apparatus for oscillating the piston, so constructed that the length of throw of the piston may be regulated and the ratio of the rate of movement of the piston to the 35 rate of movement of the driving mechanism may be adjusted.

Other objects will appear in the course of the following description.

40 My invention is illustrated in the accompanying drawings wherein:

Figure 1 is a side elevation of a force feed lubricator constructed in accordance with my invention, the auxiliary pressure chamber and the piston chamber being in section. 45 Fig. 2 is a vertical section through the piston chamber, the gearing connected to the piston being shown in elevation. Fig. 3 is a perspective detail view of the piston.

Corresponding and like parts are referred 50 to in the following description and indicated in all the views of the accompanying drawings by the same reference characters.

Referring to the drawings, 2 designates a pipe leading to the cylinder of an engine 55 or pump and connected in any suitable manner to the upper end of a sight feed glass

3. This sight feed is of any suitable construction and forms no part of my invention, and hence requires no particular description. Leading into the lower end of 60 the sight feed glass is a pipe 4 which in turn leads to the pumping mechanism as will be later described.

Disposed in the length of the pipe 4 is a T 5 connected to a pressure chamber 6. This 65 pressure chamber is formed, as illustrated, in two sections, one of which is adjustable upon the other. The pressure chamber consists of the body section 7 which is exteriorly screw threaded and a cap 8 which is 70 interiorly screw threaded so as to be adjustable up or down upon the body 7.

Disposed within the chamber 6 is a piston 9 having a spindle 10 which extends through the cap, and surrounding this spindle and 75 bearing at one end against the cap and at the other end against the piston is a spiral spring 11 which acts to force the piston downward and which resists any upward movement of the piston with a strength depending upon the position of the cap 8. If the cap 8 is screwed down upon the body 7, the spring will be under greater tension than if the cap 8 is screwed outward. Thus 80 the tension of the spring may be adjusted at 85 any time.

Connected to the pipe 4 is a pump casing 12. This casing is formed on one face with a segmental groove 13 forming a piston space, and at one end is connected by 90 means of a duct 14 to the pipe 4, the casting forming one section of the pump casing being threaded as at 15 for engagement with the pipe 4. The outer end of the duct 14 is enlarged as at 16 so as to form a valve chamber within which is disposed a ball valve 17 which opens to pressure within the duct but closes to pressure within the pipe 4. This valve chamber is closed by means of a screw 95 threaded plug 18 which when removed permits the ball to be removed or inserted. 100

The pump casing 12 is formed at one point of its circumference with an outwardly projecting hub 19 formed with a polygonal portion 20 whereby a wrench may be applied thereto and with a reduced screw threaded portion or nipple 21 for engagement in a hub 22 projecting from the lower end of a lubricant reservoir or cup 23. This lubricant reservoir or cup is closed at its 110 upper end by a cap 24 and extending across the upper end of the reservoir or cup is a

strainer 25. The cap 24 is formed with a filling opening 26 whereby the lubricant may be poured into the cup at any time desired.

The hub 19 is formed with a duct or passage 27 which opens into the piston space 13 intermediate its ends. The section 12 of the casing is formed at its center with a recess 28 opening upon the outer face of the section 12 and mating with the section 12, and fitting against the outer face thereof is a section 29 comprising an approximately circular plate held in place by screws 30 and formed at its center with a socket or bearing 31 for the reception of the end of a central shaft or spindle 32. Mounted upon this shaft is a sleeve 33 having an outwardly projecting arm 34, and extending in the arc of a circle from this arm 34 is a segmental piston 35 formed at its end with a head 36 adapted to receive a gasket or packing 37, this packing being held in place by a plate 38 and a screw 39. The body portion 12 of the pump casing is slotted as at 40 to permit the arm 34 to oscillate so as to carry the piston head from the position shown in Fig. 1 to the extremity of the piston space 13.

As a means of oscillating the piston 35, I have provided a ratchet wheel operatively connected for intermittent rotation in one direction to any suitable operating mechanism of the engine or pump to be lubricated and operatively connected to the shaft 32. As illustrated, the main section 12 of the casing is provided with a projecting bracket 41 which extends downward and outward from the section 12 and carries at its end a shaft 42. Upon this shaft is mounted the ratchet wheel 43, this ratchet wheel being cast on the shaft and having a projecting wrist pin 44 upon which is mounted a pitman or connecting rod 45 pivotally connected at its extremity to an arm 46 projecting from and attached to the shaft 32 by a set screw. It will be seen that upon a rotation of the wheel 43, the arm 46 will be oscillated, thus oscillating the shaft 32 and the piston.

As a means for securing a rotation of the wheel 43, I provide upon the extremity of the shaft 42 a crank handle 47 whereby the wheel 43 may be manually rotated, and I also provide an arm 48 rotatably mounted upon the shaft 42 and provided with a pawl 49 meshing with the teeth of the ratchet wheel 43 upon movement in one direction but sliding over said teeth upon movement in the other direction. In order to prevent a reverse rotation of the wheel 43 while the pawl 49 is slipping over the teeth of the wheel, I may provide the pawl 50 pivoted upon the bracket 41 and engaging said teeth. The arm 46 is formed with a plurality of perforations 52 whereby the connecting rod 45 may be adjusted with relation to the axis of the piston, and I also form the arm 48 with

a plurality of perforations 53 whereby a rod 56 may be connected to the arm 48. By adjusting the rod 56 in any one of the holes 53, the throw of the arm 48 may be adjusted and as a consequence the degree of rotation of the ratchet wheel and the degree of movement of the piston be adjusted.

The lubricator may be supported in any suitable manner but I have shown for this purpose a bracket 57 engaging the hub 22 and attached in any suitable manner to some fixed support.

The operation of my invention is as follows: The oil flows by gravity into the opening in the pump casting when the piston head or plunger is back in the position shown in Fig. 1, and when the piston moves forward it closes the port forming the mouth of the duct 27 and forces the oil along the space 13 by the check valve 17 and into the pipe 4 in which there is a pressure corresponding to the steam pressure. The degree of movement of the piston 35 will of course depend upon the perforation 53 within which the rod 56 is fixed and upon the adjustment of the connecting rod 45 with relation to the arm 46. It is possible to so adjust the mechanism that upon each reciprocation of the rod 56 the piston 35 will travel from the duct 27 to or nearly to the extremity of the piston space. Thus it is possible to shorten the stroke of the arm 48 so that a number of oscillations of the arm 48 will be necessary to cause the piston to travel through the entire length of the space 13 and to cause its complete retraction. Thus by proper adjustment the oil may be fed rapidly or slowly, depending upon circumstances and, furthermore, it will be noted that this adjustment may be made very rapidly and without stopping the engine inasmuch as it is only necessary to throw out the dog or pawl 49, thus disconnecting the oscillating arm 48 from the wheel 43 and stopping the action of the pump through not stopping the engine. It will also be seen that oil may be poured into the cup or reservoir 23 at any time without having to stop the engine or disconnect the lubricator.

The function of the pressure chamber 6 is to cause a uniform pressure of oil at all times. As the piston 35 moves forward, oil is forced into the pipe 4 against the pressure therein and some of the oil will be forced up into the chamber 6 against the force of the spring pressed piston 9 so that this chamber 6 will always have a certain amount of oil therein, and when the piston 35 is retracted, the force of the spring 11 will force the piston 9 down, thus forcing out oil from the auxiliary chamber 6 into the pipe 4 and into the engine. Thus it will be seen that a uniform flow of lubricant is secured continuously.

The throw of the pump piston may be regulated by adjusting the lever 48 which is attached to the shaft by a set screw.

What I claim is:

- 5 1. A force feed lubricator including a pump casing having an arcuate piston space therein, one end of the piston space having a discharge duct leading therefrom, an outwardly opening valve in the discharge duct
- 10 controlling the same, a lubricant reservoir opening into the piston space intermediate its ends, a transverse shaft passing through the casing, an arm on the shaft and disposed within the pump casing, an arcuate piston
- 15 supported on said arm and traveling in the arcuate piston space, said piston having a head at one end and the body of the piston being adapted to close the duct from the lubricant reservoir, and means for oscillating said shaft.
- 20 2. A force feed lubricator including a pump casing having an arcuate piston space therein, one end of the piston space having a discharge duct leading therefrom, a valve
- 25 controlling the discharge duct, a lubricant reservoir opening into the piston space intermediate its ends, a transverse shaft pass-

ing through the casing, an arm on the shaft, an arcuate piston supported on said arm and traveling in the piston space, said piston having a head at one end and the body of the piston being adapted to close the duct from the lubricant cup, an arm on the shaft, and means for oscillating said arm.

3. A force feed lubricator including a pump casing circular in form and made in two sections, one of said sections having formed therein an arcuate piston space having a duct leading therefrom and terminating in an exteriorly screw-threaded nipple, said nipple being adapted to support an oil reservoir and being tubular, the other of said sections mating with said first section and being formed with a central bearing, a shaft passing into said bearing, an arcuate piston mounted on said shaft and moving in the piston space, and means whereby the shaft may be oscillated.

In testimony whereof I affix my signature in presence of two witnesses.
